United States Patent Office

Des. 188,057
Patented May 31, 1960

188,057

TABLE

Le Roy H. Rasmussen, 693 Chatto Place,
Los Angeles, Calif.

Filed Oct. 13, 1959, Ser. No. 57,921

Term of patent 7 years

(Cl. D33—14)

I claim:

The ornamental design for a table, substantially as shown.
